UNITED STATES PATENT OFFICE.

WILLIAM A. SCHLEICHER, OF CLEVELAND, OHIO.

DESIGN FOR A LICENSE-TAG BRACKET.

43,681.

Specification for Design.

Patented Mar. 4, 1913.

Application filed December 12, 1912. Serial No. 736,421. Term of patent 14 years.

To all whom it may concern:

Be it known that I, WILLIAM A. SCHLEICHER, a citizen of the United States, residing at Cleveland, in the county of Cuyahoga and State of Ohio, have invented a new, original, and ornamental Design for License-Tag Brackets, of which the following is a specification, reference being had to the accompanying drawing, forming part thereof.

The figure is a perspective view of a

license tag bracket, showing my new design.

I claim:

The ornamental design for a license tag bracket, as shown.

In testimony whereof, I have hereunto set my hand.

WILLIAM A. SCHLEICHER.
